UNITED STATES PATENT OFFICE.

GEORGE A. TAYLOR, OF BOSTON, MASSACHUSETTS.

PISTON FOR INTERNAL-COMBUSTION ENGINES.

Application filed January 26, 1923. Serial No. 615,114.

My invention relates to pistons for internal combustion engines. The piston embodying my invention comprises a head and a skirt, cast in one piece, but separated from each other in part by circumferential slots, the skirt being rendered compressible and resilient by a vertical slot, and the whole being constructed and arranged as will be described. By the head is meant not only 5 that portion of a one-piece or unitary piston which forms the upper end of the body, but also which has the grooves for the piston rings. The skirt is that portion of the piston below the head and is of generally cylindrical shape.

As is well known to those skilled in the art, pistons for internal combustion engines, and particularly aluminum pistons, wear rapidly and when worn permit oil to pass 10 from the crank case to the combustion space of the cylinder. Wear also causes loss of compression, loss of power, and noises known as "slap". Furthermore, new pistons have always been given a considerable 15 clearance varying in amount about one one-thousandth of an inch for cast iron each inch of diameter, the amount depending upon the conditions under which the piston is to be used and the materials of which it and the 20 cylinders are made. In general practice, about double the clearance is provided for aluminum pistons as for cast iron pistons, owing to the higher coefficient of expansion 25 of aluminum and its alloys, and therefore more difficulty from loss of compression, oil pumping, and slapping has been experienced 30 with aluminum pistons than with cast iron pistons. Furthermore, aluminum wears more rapidly than cast iron, increasing the 35 clearance on one side of the piston and accentuating the difficulties.

The piston embodying my invention is made with a maximum normal diameter greater than that of the cylinder in which 45 it is to be inserted and is believed to be the first piston which is made in this manner. In practice, I make the entire skirt compressible by slotting it, and grind, or otherwise form, the skirt with a taper, the greatest 50 diameter being at the bottom and being greater than the diameter of the cylinder, while the least diameter of the skirt is at the junction of the skirt with the head and when cold is slightly less than the diameter 55 of the cylinder. When the piston is forced into the cylinder, the skirt is compressed

circumferentially and the lower edge contacts with the inside of the cylinder wall, leaving a clearance of increasing amount above the line of contact extending to the 60 top of the skirt. This is the situation when the parts are cold, but it will be understood that when hot, the exterior of the piston skirt and the interior of the cylinder conform more closely in size and shape. The 65 result is that the piston, having when cold only a small area of contact with the cylinder wears in rapidly, adapts itself quickly to the slight variations from a true circle, which always exist in the cylinder of an 70 internal combustion engine, and soon forms a practically tight joint therewith. In practice, the lower edge of the piston acts as an oil scraping edge.

To produce a better contact with the 75 cylinder walls, the skirt is partly severed from the head by three circumferential slots intersected by longitudinal slots in the skirt, these slots forming resilient areas or tongues. Between the circumferential slots 80 are unsevered portions, two of which are located above the wrist pin bosses, forming an integral three-point connection between the head and skirt.

To improve the wearing qualities of the 85 piston, particularly when the same is made of aluminum, I provide around the bottom of the skirt an inlay of cast iron or other suitable material, which forms a wearing surface of the best possible character. I 90 am aware that piston rings on the bottom of a piston have heretofore been used, but I believe myself to be the first to employ an inlay of cast iron or other suitable metal, that is, an area, the metal of which is practically integral with the adjacent metal, but is of a different kind and has a surface 95 which is flush with the remainder of the peripheral surface of the cylinder. A convenient method of producing such an inlay 100 is to cut a groove in the surface of the piston, place therein a ring of cast iron or other suitable metal, then drive the ring forcibly into the groove, and finally machine or grind the entire surface of the piston to 105 render the adjacent surfaces flush with each other.

Other novel features of my invention will appear hereafter.

The invention will be fully understood 110 from the following description when taken in connection with the accompanying draw-

ings, and the novel features thereof will be pointed out and clearly defined in the claims at the close of this specification.

In the drawings:

5 Fig. 1 shows, in section, a portion of a cylinder having therein a piston, the piston being shown in elevation.

Fig. 2 is a view of the piston before the finishing cut is taken or the grinding operation performed.

10 Fig. 3 is a similar view after the above operations have been performed.

Fig. 4 is a view showing the opposite side of the finished piston.

15 Fig. 5 is a section on line 5—5 of Fig. 3, the scale being reduced.

Referring now to the drawings, at A is shown a portion of the cylinder in which the piston is to be used. This is designed to 20 be a true cylinder, that is, is of uniform diameter throughout its entire length and conforms thereto as closely as the processes of manufacture will permit. The piston embodying my invention has a skirt B and head C which are integral, ring grooves being formed at D to receive piston rings E, F and G. The lands H between the ring grooves do not contact with the cylinder wall being of a diameter less than that of 25 the cylinder, and in this respect being of the well-known construction.

The skirt B is partly severed from the head by a series of circumferential slots, three in number. One of these slots, 11, is 30 located on the so-called compression side of the piston, that is, on the side opposite to that on which the reaction, due to the explosion, exerts pressure and extends from one piston pin boss 12 to the other boss 13.

40 This slot 11 is intercepted by a substantially vertical slot 14, extending upward from the bottom of the skirt and thereby rendering the skirt compressible. On the explosion side of the piston are two circumferential slots 15 and 16 separated by an unsevered or integral portion 17. These two slots extend from the unsevered portion to points about adjacent the piston pin bosses 12 and 13. The head C is, therefore, connected to the skirt B at three points, which will clearly be seen in Figure 5, in which they are designated respectively 17, 18 and 19. This construction supports the head firmly on the skirt so that there is ample 50 strength to withstand the shock of the explosion and at the same time permits the skirt to be compressed circumferentially and to carry off the heat to which the head is subjected. All of the circumferential slots 55 11, 15 and 16 are preferably located in the bottom of the lower piston ring groove G. Surrounding each of the pin bosses 12 and 13 on the outside of the piston is a relieved area 30 which has a slightly reduced diameter 60 and does not contact with the cylinder wall.

Adjacent the edges of the relieved area on the explosion side of the piston are two substantially vertical closed end slots 20 and 21 which intercept the circumferential slots 15 and 16. This construction leaves two 70 areas or tongues 22 which are relatively freely yielding, while the area below the unsevered portion 17 is relatively unyielding and rigid. The piston, therefore, has ample bearing surface on the explosion pressure 75 side while at the same time means is provided by which the piston rapidly adjusts itself to the shape of the cylinder and the tendency to slap is reduced.

In the preferred form of my invention, I 80 make the body of the piston of aluminum and place near the bottom edge an inlay 24 of cast iron. In practice, I cut a groove in the peripheral surface of the skirt and then force into it a ring 24 of cast iron, which 85 has been split to permit it to snap over the bottom of the piston. Thereafter, the ring is driven forcibly into the groove and wedged tightly therein by any suitable method, as, for instance, by rolling. This secures the inlay in place permanently. Next I turn down and grind the surface both of the piston and of the ring so that they will be flush, and the inlay will form, to all intents and purposes, a portion of the skirt 95 in the piston. In practice, the slot 14 is not sawn until after the surface of the skirt and the inlay has been finished. While I have shown in the drawings the inlay as in the shape of a ring forced into a groove, I 100 do not limit myself to this construction, since the inlay may be made of any desired shape and may be made of other suitable metals, as, for instance, of soft bronze or babbitt.

As previously stated, the skirt of the piston is tapered, the skirt being larger at the bottom than it is adjacent the head. Furthermore, the bottom of the skirt is larger than the bore of the cylinder in which it is to be used, while the top of the skirt is 110 smaller. For instance, the diameter at the bottom of the skirt, as indicated in the drawings, may be .005 of an inch larger, while the top may be made .002 of an inch smaller than the cylinder in which it is to 115 be used. It will be understood, of course, that the head is considerably smaller than the diameter of the cylinder and the piston is therefore insertable in the cylinder in the ordinary way. In practice, the piston is 120 driven or otherwise forced into the cylinder, and this compresses the skirt.

When in place in the cylinder and the parts are cold, the bottom edge of the skirt rests against the cylinder wall, and there 125 is a clearance of increasing amount all the way up the skirt to the head. Since the skirt is somewhat elastic and, theoretically at least at this time, has contact with the cylinder only along a line, the friction be- 130

tween the piston and cylinder is very small. In practice also the two areas or tongues 22 spring outwardly and contact with the wall, serving to steady the piston. When the 5 parts are hot, as is the case in use, and the piston, constructed as described, is run in, the bottom edge wears so that the area of contact between the cylinder wall and the piston increases or widens and extends upwardly until it includes the surface of the inlay wholly or in part. The rapidity with 10 which the bottom edge of the piston wears in produces a tight joint between the piston and cylinder immediately, and the piston 15 adapts itself almost instantly to the variations from the cylindrical which always exist in engine cylinders.

I find in actual practice that pistons made as described are tight from the beginning 20 and that engines fitted with new pistons, the cylinders having been worn somewhat out of round, can be used at once without lapping in the piston.

While I have described herein the preferred embodiment of my invention as comprising an aluminum piston having a cast iron inlay, it is to be noted that I do not limit myself to the use of these particular materials except in so far as the materials 30 are specifically claimed hereafter.

What I claim is—

1. A one-piece piston having a skirt and piston pin bearings, said skirt having relieved areas surrounding said bearings to 35 form segmental bearing portions between them and an annular bearing portion below them at the lower end of the skirt, the normal diameter of said annular portion being greater than that of said segmental portions, 40 one of said segmental portions being slotted to render said skirt compressible, and the other of said segmental portions being separated from said relieved areas.
2. A piston having adjacent the head a 45 circumferential slot on the compression side and on the explosion pressure side two circumferential slots separated by an integral area connecting the skirt and head.

3. A piston having on the explosion pressure side two resilient areas formed by 50 closed circumferential and longitudinal slots separated by an integral area connecting the skirt and head, said piston having on the compression side two resilient areas formed by a closed circumferential slot and 55 a longitudinal slot extending to the edge of the skirt.

4. The unitary piston the skirt of which is separated from the head by slots, except at three points, two of which are located 60 above the piston pin bosses and the third of which is on the explosion pressure side.

5. The unitary piston for internal combustion engines having an integral head and skirt separated from each other by slots except at three points, two of said points being over the piston pin bosses and the third being on the explosion pressure side of the piston, the explosion pressure side being relatively non-resilient and the opposite side 70 being relatively resilient.

6. The improved piston for internal combustion engines composed of a body of aluminum or an alloy thereof and having near the bottom a ring of cast iron inlaid in the 75 peripheral surface and flush with it, the skirt of said piston being compressible and the diameter at the bottom being slightly greater than that of the cylinder in which it is to be used.

7. A piston for internal combustion engines having a head and a skirt separated from said head except at three places two of which are over the respective piston pin bearings and the third of which is on the 85 explosion pressure side.

8. The improved piston for internal combustion engines, comprising a head and a skirt, said skirt being separated from the head except in three places, two of which 90 are over the respective pin bearings and the third being midway circumferentially of the piston pin bearings.

In testimony whereof I affix my signature.

GEORGE A. TAYLOR.
